ELECTRIC DISCHARGE LAMP

**Ekko Oosterhuis and Gustav Zecher, Eindhoven,
Netherlands, assignors to General Electric
Company, a corporation of New York**

**Application September 3, 1931, Serial No. 561,040
In the Netherlands September 11, 1930**

3 Claims. (Cl. 176—1)

Our invention relates to electric discharge lamps and more particularly to such lamps used for the production of ultra-violet radiations.

It is sometimes desirable to add visible light waves to the spectrum of the emitted light, which consists mostly of ultra-violet rays. Up to the present time, this has been accomplished by inserting a filament in series with the electrodes of the discharge tube. It has been shown that the life of such a filament is very short due, probably, to the fact that it is disintegrated by electric discharges.

The object of our invention is to so dispose the lighting filament in the bulb as to render it free from the effects of the hereinbefore mentioned discharges. We accomplish this by placing the filament which is to emit visible light rays in a circuit separate from that of the discharge electrodes, that is, there is no physical connection between the two circuits. It seems that the filament is less subject to disintegration in this case and therefore has a longer life.

Other features and advantages of our invention will appear from the following description of species thereof.

In the drawing Fig. 1 shows a discharge device comprising our invention; and Fig. 2 is a diagrammatic view of the wiring diagram.

Referring to Fig. 1, the discharge tube comprises a bulb 10 and stem tube 11. A cathode 12 is mounted on inner lead wires 13, 14 sealed into a stem press 15 which also envelops outer lead wires 16. Two anodes 17, 18 consisting preferably of molybdenum plates, are supported by inner lead wires 19, 20 which are sealed into the stem press 15 and connected to outer lead wires 21, 22 respectively. A filament 23, consisting preferably of a tungsten coil, is supported by inner lead wires 24, 25 which are also sealed into the stem press 15, and are connected to outer lead wires 26, 27 respectively. The bulb 10 is filled with a rare gas, such as argon, at a pressure of approximately 1 mm., to which is added a small amount of mercury vapor. For this purpose a few drops of liquid mercury are placed in the bulb. By gas filling is meant not only a filling of one or more gases, but also of one or more vapors, or a mixture of gas and vapor.

Referring to Fig. 2, the anodes 17, 18 are connected to the ends of a secondary 28 of a transformer, of which 29 is the primary. The no-load potential of the winding 28 may be, for example, 50 volts. The cathode 12 is heated by a current induced in a secondary winding 30 which develops a potential of a few volts. The center of the winding 30 is connected to the center of the winding 28. An extra winding 31 is pro-

vided to supply current to the filament 23 at a potential of, for example, 7 volts.

In operation, an arc discharge takes place between the cathode 12 and anodes 17, 18. This discharge, taking place in a vapor of mercury, produces ultra-violet rays which pass through the wall of the bulb 10 which is made of a glass transmitting ultra-violet rays. The filament 23 becomes incandescent, so that the bulb may be used for purposes of illumination as well as a source of ultra-violet rays.

What we claim as new and desire to secure by Letters Patent of the United States is:

1. An electric lamp comprising a pair of solid electric discharge electrodes, a filament connected in multiple and disposed between said electrodes and another filament adapted to be heated to incandescence to provide illumination and disposed out of line with said electrodes, said second-mentioned filament being connected to a source of electrical energy separate from that to which said electrodes are connected, there being no electrical connection between the circuit containing said filament and the circuit containing the electrodes. 25

2. An electric lamp comprising a sealed envelope capable of transmitting both visible radiation and short wave ultra-violet radiation and containing an ionizable medium and a pair of solid electrodes for passage of an arc therebetween including means for initiating an arc discharge between said electrodes, and a filament in said bulb adapted to be heated to incandescence to provide illumination and disposed out of the line between said electrodes, said filament being connected to a source of electrical energy separate from that to which said electrodes are connected, there being no electrical connection between the circuit containing said filament and the circuit containing the electrodes. 40

3. An electric lamp comprising a sealed envelope capable of transmitting both visible radiation and short wave ultra-violet radiation and containing an ionizable medium and a pair of solid electrodes for passage of an arc therebetween, a filament connected in multiple and disposed between said electrodes, and another filament in said bulb adapted to be heated to incandescence to provide illumination and disposed out of the line between said electrodes, said second-mentioned filament being connected to a source of electrical energy separate from that to which said electrodes are connected, there being no electrical connection between the circuit containing said filament and the circuit containing the electrodes. 45
